VARIABLE ATTENUATOR

Ernst Weber, Mount Vernon, and John W. E. Griemann, Bellaire, N. Y., assignors to Polytechnic Institute of Brooklyn, Brooklyn, N. Y., a corporation of New York

Application March 30, 1945, Serial No. 585,656

12 Claims. (Cl. 178—44)

1

This invention relates to variable attenuators for high frequency currents and especially for currents having frequencies in the ultra-high frequency range and higher.

For many applications in laboratory measurements as well as in test equipment in the field, it is necessary to have variable attenuators available in order to either measure power output of tubes as oscillators or to regulate the power flow into special equipment.

An object of the invention is to devise a variable attenuator for high frequency currents and having a broad band characteristic.

A further object of the invention is to devise a variable attenuator which is stable in its operation and accurate in its performance.

Broadly the invention involves a transmission conductor having an attenuator section of relatively high resistance by comparison with the adjacent sections and providing the necessary maximum attenuation. The high resistance section is formed with a wall thickness preferably less than the depth of penetration (skin depth). A conductive shunting member is arranged in closely spaced relation with the attenuator section and is movable parallel therewith to provide a parallel transmission path in shunt to a variable portion of the attenuator section.

In the preferred forms of the invention illustrated herein the attenuator section is formed as a tubular section of the inner conductor of a coaxial cable, and the shunting element comprises a conductive plunger movable into the attenuator section, but it is apparent that when embodied in a single transmission conductor the attenuator section may be formed as a flat thin conductor and the movable shunting member would be a flat plate-like element.

The variable attenuators of the present invention involve the use of metal film attenuator units of the type disclosed in co-pending applications Serial No. 540,347, filed June 14, 1944, and Serial No. 581,195, filed March 6, 1945.

Two different embodiments of the invention are illustrated in the accompanying drawing in which:

Figure 1 is a longitudinal sectional view of one construction of a variable attenuator;

Figure 1a is an enlarged sectional view of part of the attenuator unit showing the operation of the matching cone on the shunting plunger;

Figures 1b and 1c are fragmentary views showing modified forms of plungers;

Figure 2 is a longitudinal sectional view showing another form of attenuator construction; and

2

Figure 3 is a sectional view of Figure 2 taken along the line 3—3.

The attenuator illustrated in Figure 1 is constructed as a unitary assembly which may be inserted in a coaxial line. In this arrangement the attenuator unit is mounted within a cylindrical casing formed of two linear sections 1 and 1a of a metallic tube detachably joined together by a suitable coupling 1b. The attenuator unit 2 is mounted at the center of the casing and forms a linear section of the center conductor of the coaxial cable. The attenuator unit is constructed in accordance with copending application Serial No. 540,347, and is formed of an insulating tube having bullet type connectors 2a and 2b at the ends thereof which engage sockets formed in the ends of center conductor sections 3a and 3b mounted in the two sections of the attenuator casing. A thin metallic film is deposited on the outer surface of the insulating tube to provide the required attenuation in the current transmitted through the attenuator assembly. The attenuator film is very thin, preferably only a fraction of the depth of penetration (skin depth), although greater thicknesses may be used up to twice the depth of penetration. The film on the end sections of the tube indicated at 2a' and 2b' is made thicker than the film on the central section of the attenuator unit, thus providing compensating sections on the ends of the attenuator unit to prevent wave reflections from the attenuator, as more fully described in copending application Serial No. 581,195, filed March 6, 1945. The supply cable (not shown) may be connected either to the left end of tubular section 1a or to the end of a stub extension 1a'. As shown in Figure 1, the supply cable would be connected to the stub extension 1a', and the left end of section 1a is closed by a plug 1c which is so positioned that its inner face is located at effectively one-quarter of a wave length from the axis of stub extension 1a'. In case the supply cable is connected to the left end of section 1a, the plug 1c would be removed and placed in the end of extension 1a' and located so that its inner face will be positioned at effectively one-quarter of a wave length from the axis of the center conductor 3a. A center conductor section 3a' is mounted within stub 1a' and connected with the center conductor section 3a.

The outgoing cable or the apparatus to be tested is connected to a stub extension 1d on tubular section 1, and the right end of section 1 is closed by a plug 1e, the inner face of which is located at effectively one-quarter of a wave

length from the axis of stub $1d$. A center conductor section $3b'$ is mounted within stub $1d$ and is connected with center conductor section $3b$. That part of casing section 1 extending to the right of stub $1d$, and the corresponding part of inner conductor $3b$ constitutes effectively a quarter-wave stub support for the right end of the attenuator unit 2 and center conductor $3b'$.

It will be understood that the connections of the two cables may be reversed, that is, the incoming cable may be connected to extension $1d$ and the outgoing cable to extension $1a'$.

In order to provide for variation of the attenuation produced by the attenuator unit 2 , the center conductor section $3b$, and the bullet connector $2b$ of the attenuator unit are provided with a center bore in which is mounted a metallic plunger 4 formed as a metallic rod or tube having an outside diameter which will freely slide within the insulating tube carrying the attenuator film. The right end of plunger 4 extends beyond the end of the attenuator casing and is provided with a detachable head 5 . A rack 6 is arranged on the outside of the casing 1 parallel with plunger 4 and is connected at one end to the plunger head 5 . This rack passes through a slot formed in block 7 carried by tube 1 and is engaged by a driving gear 8 mounted on a shaft $8a$ journaled in the block 7 . By rotating the shaft $8a$, the plunger may be moved in and out of the attenuator unit to various positions through the action of gear 8 and rack 6 . It will be understood, however, that rack 6 and gear 8 are not essential and the plunger may be moved manually by grasping the end of the plunger or by grasping the head 5 .

By providing an index pointer $6a$ on rack 6 , the attenuator may be calibrated in decibels marked on a scale arranged parallel with the path of travel of the pointer $6a$, for example, the scale may be inscribed on the outer surface of tube 1 , or it may be inscribed on a separate element. Various other arrangements for driving the plunger are possible as will be understood by those skilled in the art.

As the plunger 4 moves into the attenuator unit, the end of the conductive plunger to the left of the bullet connector $2b$ provides a parallel path for the current flowing through the attenuator unit, and the plunger, in effect, serves to shunt a variable part of the attenuator film. Accordingly, the amount of attenuation produced by the attenuator unit may be varied by varying the position of the plunger 4 within the attenuator unit. Lowest attenuation is obtained when the plunger is fully inserted into the unit, and greatest attenuation is obtained when the plunger is fully withdrawn from the unit.

For the purpose of preventing reflection from the end of the plunger 4 , a matching element $4a$ in the form of a conductive cone is attached to the end of the plunger 4 . This cone may be formed as a separate element attached to the plunger or it may be an integral part of the plunger. The matching cone has a length almost equal to, but somewhat less than, one-quarter of the wave length of the mid-band frequency. The diameter of the cone at the small end is as small as possible but must have enough mechanical strength for self-support. The cone $4a$ acts as an antenna-like attachment to the plunger for guiding the energy out from the plunger to the film, or from the film to the plunger, and causing a gradual transition of energy flow from the attenuator film into the conductive plunger, or vice versa. Figure 1a is an enlarged sectional

view of a part of the attenuator unit showing how the cone $4a$ acts as a transition element for gradually transferring the spherical waves from the plunger 4 to the attenuator film on the outer surface of tube 2 .

In use of the movable plunger in actual practice, the plunger need not be withdrawn so that the end of section 4 of the plunger passes beyond the inner boundary of the matching section $2b'$. In case accurate matching is not required, the matching section $2b'$ could be omitted, and in this case the plunger may be withdrawn until the end of section 4 reaches the inner end of bullet connector $2b$.

Other arrangements for providing a matching section on the end of plunger 4 are possible. For example, the plunger might be formed of an insulating tube which slides freely within the attenuator unit and the main conductive section 4 of the plunger would be formed of a metallic coating or film carried by the tube, while the matching section $4a$ would be formed of a linear section of coating or film having a higher resistance than the main section 4 . Such an arrangement is shown in Figure 1b. Also, the film on the matching section could be constructed so that it changes in resistance gradually along its length, having a low value at the point of the junction with the section 4 and increasing in value to the end of section $4a$. Finally, the matching section on the end of the plunger could be formed as a series of wedge-shaped strips of metallic film having their bases in contact with the section 4 and extending to the end of section $4a$ as shown in Figure 1c.

The broad-band characteristic of the attenuator is due mainly to the matching element or transition element carried by the shunting plunger and to the matching sections at the ends of the attenuator film, and especially the matching section $2a'$.

Figure 2 is a fragmentary showing of a modified arrangement of attenuator unit for incorporation in a straight section of a coaxial cable. Elements having the same functions as corresponding elements in Figure 1 are represented by the same reference numerals. In this arrangement 1 indicates the outer tubular casing of the attenuator assembly which is connected to the outer conductor of the supply cable not shown, and 3 indicates the inner conductor which in this case is also hollow. $3a$ and $3a'$ indicate a T-shaped mounting for supporting the inner conductor in a stub extension $1'$ of casing 1 . The length of the stub is fixed at effectively one-quarter wavelength to prevent wave reflection from the mounting. The attenuator unit 2 is supported in line with the head $3a$ of the mounting, and this head is formed with a central bore in which is mounted the plunger 4 which may slide to the right into the attenuator unit 2 or to the left into center conductor 3 . A rack is formed on one side of the plunger 4 , or a separate rack may be secured to the plunger, and this rack is engaged by a pinion 9 carried by a shaft 10 mounted in a central bore formed in the support $3a'$ and extending out of the stub $1'$. Shaft 10 has a driving wheel or gear $10a$ mounted on the end thereof which may be rotated by hand or through any suitable driving arrangement.

The arrangement shown in Figure 2 may involve any of the structures described above for the matching section $4a$. From the foregoing description of operation of Figure 1 it will be apparent that the plunger 4 may be advanced into

or withdrawn from the attenuator unit 2 to control the amount of attenuation produced by the unit.

It will be noted that in both forms of the invention disclosed in Figures 1 and 2, the shunting element for the attenuator section is adjusted by means of a movable element introduced into the cable through an effective quarter-wave stub support for the inner conductor.

We claim:

1. A loss-producing variable attenuator for high frequency currents comprising in combination, an insulating tube having a thin metallic film on the outer surface thereof, said film having a thickness of the order of the depth of penetration of said currents and presenting substantial resistance to the flow of said currents, and a conductive plunger mounted for movement within said tube but out of contact with said film.

2. A loss-producing variable attenuator for high frequency currents comprising a thin metallic film in tubular form and having a thickness of the order of the depth of penetration of said currents and presenting substantial resistance to the flow of said currents, and a conductive plunger arranged for movement into said tubular film but out of contact therewith.

3. A variable attenuator for high frequency currents comprising a tubular conductor having a high resistance section formed of a thin metallic film joined to a low resistance section, a conductive plunger mounted coaxially with said tubular conductor and arranged so that one end thereof may slide into said high resistance section, and means embodied in said plunger at the end thereof for preventing wave reflection from the joint between said high resistance section and said low resistance section.

4. A variable attenuator structure for high frequency currents comprising a conductor having a low resistance tubular section and a high resistance tubular section having a thickness of the order of the depth of penetration of said currents, and a conductive plunger mounted within said low resistance tubular section and being arranged to be moved into said high resistance tubular section but out of contact therewith.

5. A variable attenuator according to claim 4 wherein said high resistance section of the conductor has a wall thickness less than the depth of penetration.

6. A loss-producing variable attenuator for high frequency currents comprising a tubular high resistance conductor section having a wall thickness of the order of the depth of penetration of said currents, and a conductive plunger arranged to slide within said tubular conductor section but out of contact therewith to provide a transmission path in parallel with a variable portion of said tubular conductor section.

7. A variable attenuator for a coaxial cable in which the center conductor of the cable is supported by an effective quarter-wave stub mounting, the combination of a tubular section of the inner conductor of said cable located adjacent said mounting and having a wall thickness of the

order of the depth of penetration, a conductive plunger arranged to slide within said tubular section to provide a transmission path in parallel with a variable portion thereof, and means located within the center support of said stub mounting and extending out of the end of said mounting for adjusting the position of said plunger.

8. A variable attenuator according to claim 7 wherein the cable sections on opposite sides of said stub mounting are in axial alignment and said stub mounting is arranged at right angles to the axis of said cable, and wherein said conductive plunger is shifted axially of said cable by means of a rack and pinion, the pinion having a rotary shaft journaled in the center support of said stub mounting and extending out of the end of said mounting.

9. A variable attenuator according to claim 7 wherein the cable sections located on opposite sides of said stub mounting are arranged at right angles to each other, and said stub mounting is arranged in axial alignment with one of said sections, and the conductive plunger of the attenuator is provided with a rod extension passing through the tubular center support of said stub mounting and extends beyond the end of said mounting.

10. A variable attenuator structure for high frequency currents comprising a conductor having a low resistance tubular section and a high resistance tubular section joined to said low resistance section, and a conductive plunger mounted within said low resistance tubular section and being movable into said high resistance tubular section without contact therewith, and means embodied in said plunger at the end which enters said high resistance section for preventing wave reflection from the joint between said two conductor sections.

11. A variable attenuator according to claim 10 wherein said reflection preventing means comprises an end section of said plunger formed into generally conical shape with the base thereof located at the end of the plunger.

12. A variable attenuator according to claim 10 wherein said reflection preventing means comprises an end section of said plunger having a different characteristic impedance from the main body of said plunger.
